UNITED STATES PATENT OFFICE.

SAMUEL J. EVANS, OF BLUEFIELD, WEST VIRGINIA.

MOTOR.

No. 846,293.

Specification of Letters Patent.

Patented March 5, 1907.

Application filed August 26, 1905. Serial No. 275,885.

To all whom it may concern:

Be it known that I, SAMUEL J. EVANS, a citizen of the United States, and a resident of Bluefield, in the county of Mercer and State of West Virginia, have invented a new and Improved Motor, of which the following is a full, clear, and exact description.

My invention relates to motors, and has for its object to provide a motor which is simple, cheap, and efficient in operation, and one in which the water of condensation is drained off without the use of cocks.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a side elevation, partly in section, of the improvement, the section being on line 1 1 of Fig. 2. Fig. 2 is a front view, partly in section, and on a smaller scale; and Figs. 3, 4, and 5 are diagrammatic sectional views of the valve-chamber and valve, Fig. 3 illustrating the valve out of operation or in a position of rest, Fig. 4 in positive lines illustrating the valve in position to force the working piston upward and in dotted lines in position to force said working piston downward, and Fig. 5 illustrates the position of the valve when the cylinder containing the working piston is to be drained.

A pedestal C', preferably of skeleton construction and having a flat top, is secured in any approved manner upon the cross-beams a^4 , and on this pedestal C' the lower open end 40 of a cylinder C is bolted or otherwise secured in a steam-tight manner, the cylinder being closed at its upper end by a suitable head 19. A piston 20 is mounted to slide in the cylinder C, and this piston is provided with a rod 45 21, which passes through an opening in the central portion of the pedestal C' and through a stuffing-box 22, provided at said point.

A valve-chamber D is formed preferably integral with the pedestal C' at one side just 50 below the cylinder C, and integral with the lower portion of the said valve-chamber D an exhaust-chamber 27 is produced, which exhaust-chamber is provided with ports 28 and 29, leading into the end portions of the valve-chamber. The ports 28 and 29 are preferably connected with a single pipe 30, which

conducts the exhaust wherever desired. At the same side of the valve-chamber a pipe 31, adapted to carry live steam, is introduced into the said valve-casing about centrally 60 between the exhaust-ports 28 and 29. Two ports 32 and 33 are located at the opposite side of the valve chamber or casing D. The port 32, which is located adjacent to one end of the valve-casing but is not in registry with the opposing exhaust-port 28, connects with the cylinder C at its bottom, as is best shown in Fig. 2, and the other port 33 is in communication with the valve-chamber near its opposite end but out of alignment with the opposing exhaust-port 29. This latter port 33 is connected with a passage-way 34, erected upon the exterior of the cylinder C, and this passage-way 34 is closed except where it connects with the port 33 and at its upper portion 75 with the upper part of the cylinder C, which latter connection is effected by producing a suitable opening 35 in the said cylinder, as is shown in Fig. 1. Thus the port 32 supplies steam to the bottom of the piston 80 to raise the same, and the port 33 supplies steam above the piston to lower the same.

The valve D', as shown in Figs. 3, 4, and 5, is practically a piston-valve and is provided with an annular centrally-located groove d 85 for the passage of steam. The position of the valve D' relative to the ports above described is shown in Figs. 3, 4, and 5, in Fig. 3 the valve being shown in a cut-off position and steam being prevented from entering 90 either of the supply-ports 32 and 33, whereas in Fig. 4 the valve is shown by full lines in a position to receive steam and to conduct the said steam to the upper ports 33 and 34, exhausting at the port 28, and by dotted lines 95 the valve is shown as receiving steam and conducting it to the lower port 32.

The valve D' is provided with a rod d' , which extends out from the forward end of the valve-chamber through a suitable stuffing-box 34^a, and this rod d' is pivotally connected with a lever 35^a, pivotally attached at its upper end to a bracket 36, extending out from a beam a^2 . The lower or handle portion of the lever 35^a is mounted to slide in 105 engagement with a guide-bar 37, suitably supported at its inner end. This guide-bar is engaged by a thumb-latch 38. A pin 39 is removably located at the outer end of the guide-bar 37, and when the lever 35^a is at the 110 inside of this pin the said lever can be moved only sufficiently to carry the valve D' a suit-

able distance forward and rearward to cause the piston to ascend or descend a proper distance. When, however, it is desired to drain the cylinder and the valve-chamber, the pin 5 39 is removed, and the lever 35^a is carried out to the dotted position shown in Fig. 1, and the pin is then replaced, holding the lever in its new position. When the lever is in its extreme outer position, the valve D' is carried 10 to the extreme forward end of the valve-casing D, as shown in Fig. 5, wherein both exhaust-ports are open and both steam-ports to the cylinder and the port which supplies live steam to the valve-chamber is likewise 15 opened, thus permitting a perfect drainage and likewise permitting the cylinder being blown out, which is generally done just prior to commencing operations.

In the ordinary operation of the valve it is 20 evident that by moving it in either direction from the center steam is admitted alternately to each end of the cylinder and exhausted at opposite ends. The object of placing the valve D' at the lower end of the 25 cylinder C and the exhaust below the valve is for the purpose of draining the water or moisture resulting from condensation without the aid of cylinder-cocks as the places in which the devices are adapted to work are 30 opened and the liability of freezing in the winter is great.

It will be observed that by introducing steam into the upper end of the cylinder in the manner shown and described a cushion 35 for the piston is obtained at the upper end of the stroke, thereby preventing the piston from striking the cylinder-head.

The port 35 enters the cylinder C some 40 distance below the top, thereby producing a space above the port, and as soon as the piston passes this port a compression commences, producing the cushioning referred to. As soon as the steam is released at the 45 lower side of the piston the said compression, combined with the weight of the gate, starts the piston downward.

I desire it to be understood that air may be employed as a motive fluid instead of steam, if desired.

50 Having thus described my invention, I claim as new and desire to secure by Letters Patent—

1. In a motor, a pedestal formed with a valve-chamber, and an exhaust-chamber, the valve-chamber having in one side feed-ports, one at each side of the center of length 55 of the chamber, and in the opposite side at its

center a supply-pipe, and the exhaust-chamber having ports leading into the ends of the valve-chamber out of register with the feed-ports, a piston-valve in the valve-chamber and having an annular centrally-located groove, means for operating the valve, a cylinder having its open lower end secured upon the pedestal and into which opens one of the feed-ports of the valve-chamber, the cylinder being provided with a passage-way leading from its upper end to the other feed-port of the said valve-chamber, and a piston in said cylinder.

2. In a motor, a cylinder, a piston within the cylinder provided with a rod extending out therefrom, a valve-chamber below the cylinder, an exhaust-chamber below the valve-chamber, feed-ports extending from the valve-chamber to the top and bottom portions of the cylinder, ports connecting the exhaust-chamber with the valve-chamber, which ports enter the valve-chamber near its ends and at the sides opposite to that provided with the feed-ports, a supply-pipe which enters the said steam-chamber at the same side at which the exhaust-ports enter and at a point between said exhaust-ports, a grooved piston-valve mounted to slide in the 85 said chamber, and means for manually operating and controlling the said valve.

3. In a motor, a cylinder, a piston within the cylinder provided with a rod extending out therefrom, a valve-chamber located below the said piston, an exhaust-chamber located below the valve-chamber, a steam-feed port leading from the valve-chamber to the bottom portion of the cylinder, a second steam-feed port also leading from the valve-chamber to the upper portion of the cylinder, entering said cylinder a predetermined distance below its head, ports connecting the exhaust-chamber with the valve-chamber at the side opposite that containing the feed-ports, a discharge for the said exhaust-chamber, a steam-supply pipe which leads into the valve-chamber at a point between the exhaust-ports, a grooved piston-valve mounted to slide in the valve-chamber, and means for operating and regulating the throw of the 95 said valve.

In testimony whereof I have signed my name to this specification in the presence of two subscribing witnesses.

SAMUEL J. EVANS.
